UNITED STATES PATENT OFFICE

DONALD S. BARROWS, OF ROCHESTER, NEW YORK, ASSIGNOR, BY MESNE ASSIGNMENTS, TO THE SYMINGTON COMPANY, A CORPORATION OF MARYLAND

JOURNAL BOX

Application filed July 13, 1922. Serial No. 574,666.

My invention relates to journal box wear plates and, generally stated, involves a renewable liner of durable construction adapted to be detachably connected to the journal box of a railway car for preventing destructive wear upon the car truck pedestal jaws and the journal boxes associated therewith, the wear incident to the constant movement of the journal box with respect to the pedestal 10 being taken by the interposed wear plates or liners.

The present invention has for a principal object the provision of a flanged liner having means for clamping the liner to projections 15 on the journal box whereby the flanges on the liner engage a plurality of faces on the journal box.

Another object of the invention is to provide a wear liner for journal boxes, the upper 20 portion of the liner being positioned beneath the seat on the journal box which receives the cushioning element.

Another object of the invention is to provide in combination with a journal box a renewable liner with bendable means for detachably connecting the liner to the journal box, said means including a bendable tang adapted to be clamped over the journal box 25 projection and arranged to extend substantially parallel with the wearing face of the liner.

The invention further consists in the provision of a journal box renewable pedestal way liner which can be inexpensively manufactured and easily attached to the side wall 35 of the journal box.

There are other features of my invention as will more clearly appear from the detailed description taken in connection with the accompanying drawings chosen to illustrate the invention and in which

Figure 1 is a view in side elevation of a railway car journal box showing my improved wear plate or liner applied thereto.

Figure 2 is a detail vertical sectional view 45 on the line 2—2 of Figure 1 through a portion of the journal box showing the liner attached thereto.

Figure 3 is a detail horizontal sectional view on the line 3—3 of Figure 1 showing the

flanged liner cooperatively associated with opposite faces of the journal box.

Figure 4 is a view in side elevation of a railway car journal box illustrating a modified form of wear plate or liner embodying 55 my invention.

Figure 5 is a detail vertical sectional view on the line 5—5 of Figure 4.

Figure 6 is a detail horizontal sectional view on the line 6—6 of Figure 4.

Referring to the drawings in which similar reference characters designate corresponding parts in the several views, a railway car journal box is indicated by the numeral 1, said journal box being provided with a seat or recess 2 adapted to receive an equalizer bar, or other type of cushioning element, according to the type of car truck upon which my invention is used. The journal box is provided with a side wall 3 from which project flanges or ribs 4 forming a pair of oppositely disposed faces which, together with the side wall of the journal box, form the pedestal way. The side wall 3 is preferably thickened at the top thereof intermediate the projecting ribs 4, as indicated by the numeral 5, and provided in said thickened portion is a recess or groove 6 extending below the seat 2 at the top of the journal box. The seat or recess is shown in the shape of a V, an up-standing or vertical projection 7 being formed between said recess and the outer wall of the journal box.

The wear plate or liner 8 is preferably formed of relatively thin uniform flat steel 85 provided with an intermediate wear portion 9, said plate being adapted to fit the side wall of the journal box. Projecting flanges 10 are provided on the wear plate, said flanges being adapted to engage the opposed 90 faces formed on the ribs 4 projecting from the side walls of the journal box. The flanges 10 are angularly disposed with relation to the body portion and wearing surface of the liner, said flanges snugly fitting within the corner recesses or pockets formed at the juncture of the journal box side wall and the projecting ribs 4, as clearly shown in Figure 3.

The means detachably connecting the liner 100

to the journal box includes a bendable extension 11 provided on the upper edge of the liner, and a somewhat shorter or similar extension 12 formed on the lower edge of said liner. The extension 11 forms a tongue or tang which is bent over the projection 7 on the journal box, said tongue extending downwardly within the recess 6 and being arranged substantially parallel with the wearing surface of the liner. The tongue is firmly pressed over the projection, as shown, and the wear plate is kept, as a result, in continuous and close contact with the side wall of the journal box. The lower tongue or tang 12 is bent around the lower edge of the journal box and serves to assist in firmly holding the wear plate in position.

In Figures 4, 5 and 6 I have shown an embodiment of my present invention wherein spaced liner or wear plates 13—13 are positioned within the corner pockets or recesses formed at the juncture of the journal box side wall and each projecting rib 4. The outwardly extending flange portion 14 of each liner engages the inner vertical face of the projecting rib 4, the body portion of the liner being preferably countersunk within the side wall of the journal box, as best shown in Figure 6.

Means for attaching the liner 13 within the countersunk portion of the journal box side wall includes bendable extensions 15 provided on both body portion and flange 14 of each liner, said extensions forming tongues or tangs adapted to be clamped around the upper edge of the journal box side wall and the adjacent rib projecting from the journal box. Bendable extensions 16 are provided on the lower edge of the body portion of the liner and the flange portion 14, said extensions forming tongues or tangs adapted to snugly fit about the lower edges of the journal box side wall and adjacent projecting rib. The upper tangs are arranged so as to terminate short of the seat or recess 2 which receives the cushioning element. It will be also noted that the upper edge of the side wall of the journal box projects above the top of the box and that the tang 15 on the body portion of the liner is pressed about said upper edge and extends downwardly substantially parallel with the wearing surface of the liner. At the angle or bend of the liner the extensions are split, as indicated by the numeral 17, thereby permitting the wear plate to be angularly formed with separated tongues or tangs which can be respectively bent as hereinbefore described.

From the foregoing it will be obvious that I have produced a flanged wear plate capable of effectively lining the pedestal ways, the flanged portion of said plate resisting the wear incident to axle thrusts, as well as the wear incident to the relative vertical move-

ment between the pedestal of the truck and the journal box. It will also be seen that an advantageous attaching means adapted to firmly position the wear plate below the cushioning element seat on the journal box 70 has been provided.

I claim:

1. The combination with a journal box for pedestal trucks, and a wear plate or liner detachably connected thereto, said wear plate being formed with an angular portion adapted to engage a pair of faces on the journal box and connected to said box by bendable tongues engaging a wall portion thereof, a portion of said wall being thickened and provided with a pocket therein for receiving one of said tongues. 75

2. The combination with a journal box for pedestal trucks having a thickened wall portion formed with a pocket, and a liner connected thereto, said liner being formed with an angular portion adapted to engage one pair of faces on the journal box and having means extending into said pocket for detachably connecting said liner to the journal 85 box. 90

3. The combination with a journal box for pedestal trucks having a wall portion formed with an upwardly opening pocket with sloping sides formed in a thickened portion thereof, and a wear plate, said wear plate having a plurality of wearing surfaces, said wearing surfaces cooperating with a plurality of faces provided on the journal box and said plate provided with attaching means bent to 95 extend into said pocket. 100

4. The combination with a journal box for pedestal trucks formed with a pocket in its upper surface, and a wear plate detachably connected thereto, said wear plate having 105 a plurality of adjacent wearing surfaces cooperatively associated with adjacent faces on the journal box and provided with re-entrant connecting means considerably narrower than the adjacent wear plate surface extending 110 into said pocket. 115

5. The combination with a journal box for pedestal trucks having a seat for a cushioning element, and a wear plate detachably connected to said journal box, the uppermost 115 portion of said wear plate being arranged beneath and within the area of said seat.

6. The combination with a journal box for pedestal trucks having a seat for a cushioning element, and a liner carried thereby, said liner having a plurality of wearing surfaces cooperatively associated with a pair of faces on the journal box, and relatively narrow means detachably connecting the liner to the journal box with the uppermost portion 120 thereof positioned below and within the outline of the seat for the cushioning element. 125

7. The combination with a journal box for pedestal trucks having a seat for the cushioning element, of a projection on said jour- 130

nal box arranged beneath and alined with said seat, and a wear plate having a portion adapted to engage said projection below said seat.

5 8. The combination with a journal box for pedestal trucks having a seat for the cushioning element, of projections on said journal box, and a liner having opposite bendable portions adapted to engage said projections, 10 said bendable portions being arranged below said seat.

15 9. The combination with a journal box having a side wall portion, of a projection adjacent and extending from a thickened portion of said side wall portion, a wear plate having centrally disposed means connecting the upper end thereof to said projection, and similar means connecting the lower end of 20 said wear plate to said side wall portion of the journal box.

25 10. The combination with a journal box having a side wall portion thickened at the top, of projections therefrom, a wear plate having a main wearing surface, side surfaces angularly disposed with respect thereto, and oppositely disposed end portions on said main surface adapted to be bent about said projections, said bent end portions being arranged substantially parallel with the wearing 30 surface of said liner.

35 11. The combination with a journal box having a thickened side wall portion, of a projection therefrom, a U-shaped wear plate having an end portion bent around said projection from the main body thereof and extending substantially parallel with the wearing surface of said plate, and similar means connecting the lower end of said wear plate to the journal box.

40 12. The combination with a journal box having a seat for a cushioning element, a projection on said journal box disposed on a thickened wall portion thereof, and a wear plate having means engaging the projection below and alined with said seat.

45 13. A wear plate for journal boxes comprising a plurality of relatively flat adjacent wear surfaces arranged at an angle to each other, and relatively narrow tangs carried by said plate, arranged at opposite ends of an intermediate one of said wear surfaces, and adapted to be bent to embracing engagement with an associated box.

55 14. A wear plate of the class described comprising a plurality of relatively flat adjacent wearing surfaces arranged at an angle to each other, and oppositely arranged tangs carried by said plate, positioned on one of said wearing surfaces, and adapted to embracingly engage adjacent edge portions of an associated box.

60 15. A wear plate of the class described comprising a plurality of adjacent wearing surfaces angularly disposed with relation to each other, two of said wearing surfaces being op-

positely disposed, and another of said wear surfaces connecting said oppositely disposed wear surfaces and provided with relatively narrow tangs adapted to be bent back on themselves to connect said plate with an associated box.

70 16. A wear plate of the class described comprising a plurality of wear surfaces angularly disposed with relation to each other, two of said wear surfaces being oppositely disposed, another of said wear surfaces connecting said oppositely disposed wear surfaces, and relatively narrow bendable means provided on the top and bottom of the connecting wear surface for detachably connecting the wear plate to an associated journal box and prevent removal therefrom in any direction.

75 17. A wear plate of the class described comprising a plurality of adjacent wear surfaces, and relatively narrow flexible means provided on the opposite vertical ends of an intermediate one of said wear surfaces for being bent for detachably connecting the wear plate to a journal box.

80 In testimony whereof I affix my signature. 90
DONALD S. BARROWS.
